UNITED STATES PATENT OFFICE

2,521,042

BEACH PROTECTOR

Louis Cherwin, New York, N. Y.

Application November 29, 1945, Serial No. 631,583

2 Claims. (Cl. 135—4)

1

This invention relates to a beach protector which is adapted to be adjusted to protect a person on the beach from the rays of the sun while such person is in a sitting, standing or reclining position.

An object of the invention is to provide a device that can be folded into compact assembly for carrying the device in a suitcase or under a person's arm or in any convenient manner as desired.

The simplicity of the device and the compact manner in which it may be folded provides a device that can be easily transported and arranged in any desired manner by the user thereof.

With the above and other objects and advantages in view, the invention consists of the novel details of construction, arrangement and combination of parts more fully hereinafter described, claimed and illustrated in the accompanying drawings in which:

Figure 1 is an elevational view of an embodiment of the invention showing the device in partly extended position and a cover in use therewith;

Figure 2 is a top plan view thereof;

Figure 3 is a sectional view on the line 3—3 of Figure 1;

Figure 4 is a bottom plan view with the legs in closed position;

Figure 5 is a sectional view on the line 5—5 of Figure 3;

Figure 6 is a detailed sectional view of one of the leg joints;

Figure 7 is a view of the pivoted leg in folded position;

Figure 8 is a view of one of the fixed legs in folded position;

Figure 9 is a view of the complete assembly in folded position;

Figure 10 is a top plan view of the assembly in folded position;

Figure 11 is a view showing the device adapted for a person in standing position;

Figure 12 is a view showing the device adapted for a person in full reclining position;

Figure 13 is a bottom plan view of a modified form of the invention;

Figure 14 is a view partly in section of the legs extended, and

Figure 15 is a bottom plan view of the legs in folded position.

Referring more in detail to the drawing, the numeral 20 designates the completely assembled protector over which a cover 22 may be placed to protect a person sitting, standing or reclining thereunder.

The protector 20 comprises a hexagonal cap 55

piece 24 to which are fixed by screws 26 the L-shaped brackets 28 while the L-shaped bracket 30 is pivotally secured to the cap 24 by the bolt 32 and wing nut 34.

Legs 36 are pivotally connected to the brackets 28 and 30 by bolts 38 and wing nuts 40. The legs 36 comprise a series of spaced parallel links 42 which have the single links 44 connected intermediate their ends by bolts 46 and wing nuts 48 to form the collapsible legs as shown.

In Figures 1 to 12 inclusive, the assembly embodies the use of three legs but in Figures 13, 14 and 15, there is shown the use of four legs, two fixed brackets 28 and two pivoted brackets 30, otherwise the assembly is as previously described.

When the device is in use, the legs extend from the cap 24 as shown in Figure 3, but when it is desired to fold the assembly for transportation thereof, the pivoted leg is swung parallel to the fixed leg which is positioned at right angles thereto and the other fixed leg is swung to a position intermediate the other fixed leg and pivoted leg and the assembly assumes the position shown in Figure 3. The collapsible legs are then folded and the assembly assumes the position shown in Figure 9.

As shown in Figure 1, the protector is adapted for use by a person sitting in a chair or on the beach. In Figure 11, the device is adapted for use by a person standing or in Figure 12, the assembly is adapted for use by a person in reclining position.

It is believed the operation and construction of the device will be apparent to those skilled in the art and it is to be understood that modifications and changes in the minor details of construction, arrangement and combination of parts may be resorted to without departing from the spirit of the invention or the scope of the appended claims.

Having thus described the invention, what is claimed as new and desired to be secured by Letters Patent is:

45 1. A device of the character described, comprising a cap piece having legs secured thereto and adapted to be extended therefrom to support a covering to protect a person positioned thereunder, and the legs being collapsible and comprising pairs of parallel links having single links pivotally connecting successive pairs of the ends of said parallel links.

50 2. A device of the character described, comprising a cap piece having legs secured thereto, and adapted to be extended therefrom to support

a covering to protect a person positioned thereunder, and two of said legs being pivotally connected to means fixed on said cap piece and two of said legs being pivotally connected to means pivotally secured to said cap piece.

LOUIS CHERWIN.
